UNITED STATES PATENT OFFICE.

JOHN H. SHIMMONS, OF LAWRENCE, KANSAS.

HEATING-STOVE.

SPECIFICATION forming part of Letters Patent No. 229,193, dated June 22, 1880.

Application filed February 2, 1880.

To all whom it may concern:

Be it known that I, JOHN HENRY SHIMMONS, of Lawrence, Douglas county, Kansas, have invented a new and useful Heating-Stove; 5 and I do hereby declare the following to be a full, clear, and exact description of the same, reference being had to the accompanying drawing, forming a part of this specification, in which the figure is a vertical central 10 section.

My invention is an improvement in heating-stoves of that class in which a set of pipes lead the air through the fire-chamber into an air-chamber above, from which air-chamber 15 pipes conduct the heated air through a drum placed above the air-chamber, which drum receives the products of combustion, which further heat the air as it passes through the pipes.

My improvement consists in making the 20 heating-drum above the air-chamber of greater capacity than the fire-pot below the air-chamber, and combining with the air-chamber external-air-supplying pipes, which reinforce the 25 volume of air passing through the drum, giving a larger volume of hot air than could be obtained from the limited number of pipes which lead through the fire-pot simply, as hereinafter fully described.

In the drawing, A represents the fire-pot of 30 the stove, which is contracted at its lower portion into a grate, through which the ashes are discharged into the ash-pit B. On each side of the ash-pit, and in the back of the same, are formed chambers or compartments *a a a*, which 35 open through the bottom of the stove into the room, and from which there rise a series of air-pipes, *b b b*, which pass through the tapering bottom portion of the fire-pot to the interior thereof, and finally open into an annular 40 air-chamber above the fire-pot, the bottom of which air-chamber is formed by the annular partition *c*, and the top of which is formed by the annular partition *d*, which dips downwardly to the center, like a funnel, and is connected to the short central pipe, *e*, which 45 constitutes the discharge-flue from the fire-pot, and opens thence into a drum, C, placed above. Extending downwardly from the air-chamber, between the partitions *c* and *d*, and outside of

the fire-pot, are two fresh-air flues, D D, which 50 open through the bottom of the stove.

The air, as it rises through the air-pipes *b*, it will be seen, is heated by the direct contact of the fire, and, after passing through the air-chamber, is again subjected in the pipes E of 55 the drum to the direct heat of the hot gases which circulate in said drum about the pipes. After being thus thoroughly heated the air passes into the room from the tops of the pipes E, while the smoke and products of combustion 60 pass through the pipe F.

The object of the flues D D is as follows: The heating-drum C, it will be seen, is very much larger than the fire-pot A, and hence is able to accommodate a greater number and 65 size of air-pipes than the limited size of the fire-pot will permit. To give a larger supply of air to the drum, therefore, I employ thin pipes D, the air from which is mingled with the partially-heated air in the air-chamber, 70 which has already passed through the fire-pot flues, the combined currents then passing up through the pipes of the drum C to be reheated.

In constructing the funnel-shaped partition *d*, which forms the top of the air-chamber, the 75 object in making the same funnel-shaped or sloping to the center is to give the soot and deposited particles an opportunity to slide down into the fire-pot and be consumed.

In modifying my invention I may separate 80 the heating-drum C from the fire-pot a sufficient distance to allow the drum to be located on the story next above the stove, in which case the air-chamber and the communicating central smoke-flue, *e*, are prolonged.

Another advantage of my stove is, that it can be carried through as many stories as desired, either by one long central shaft or drum or by heating-drums in the different stories. When several drums are thus used the air for 85 one story may be taken through pipes *b*, *D*, and *E*, and for the next story it may be taken through the T-pipes P, which open sidewise into the same room where the stove is, and lead through the lower drum to the drum in 90 the story above.

Having thus fully described my invention, what I claim is—

The combination of the fire-pot A and the drum C, made larger than the fire-pot and having direct communication therewith, as described, the annular air-chamber communicating with the pipes b of the fire-pot and the pipes E of the drums, and the independent external pipes, D, communicating with the

upper annular air-chamber and supplying an additional quantity of air to the drum, as described.

JOHN HENRY SHIMMONS.
